UNITED STATES PATENT OFFICE.

JUDSON A. DE CEW, OF MOUNT VERNON, NEW YORK, ASSIGNOR TO PROCESS ENGINEERS INCORPORATED, OF NEW YORK, N. Y.

METHOD FOR USE IN SOAP-POWDER MAKING.

Application filed March 22, 1921. Serial No. 454,431.

To all whom it may concern:

Be it known that I, JUDSON A. DE CEW, a citizen of Dominion of Canada, residing at Mount Vernon, in the county of Westchester and State of New York, have invented certain new and useful Improvements in Methods for Use in Soap-Powder Making, of which the following is a specification.

This invention relates to certain steps in
10 and apparatus for use in the manufacture of
soap powder, especially in that type wherein
a mixture of soap and soda ash is atomized
into a hot chamber.

15 The object of the invention is to so intimately and smoothly mix the soap and soda ash or other alkali that the mixture does not jell or become lumpy and thereby clog the atomizer if not making atomization impossible.

20 This object is obtained by heating the soap and alkali such as soda, in liquid form separately under pressure, forcing fine streams of soap and soda to impact against each other preferably while at a temperature approximately 180° F., whereupon an intimate, uniform, smooth and exact mixture of the soap and alkali that will not jell results in a minimum of time.

To this end I have devised an apparatus
30 for carrying out the invention, one embodiment of which is herein described, it being understood however, that it is to be taken in an illustrative sense and not a limiting one.

This embodiment is shown diagrammatically in the accompanying drawings in which—

Figure 1 is an elevation showing the arrangement of the various units of the apparatus;

Figure 3 shows one of the perforated plates 22.

In the drawings, a tank 11 will be seen in which hot soap 12 is adapted to be placed under pressure. Steam coils 13 or their equivalents may be used to maintain the soap at any desired temperature indicated on the thermometer 14 and the degree of pres-

sure under which the soap is maintained is shown by the gauge 15.

A similar tank and associated parts 11', 13', 14' and 15' is provided for liquid soda 16 or other alkali.

Conduits or pipes 17 and 18 lead from tanks 11 and 11' respectively to a mixing chamber 19 equipped with a thermometer 20. Adjacent the ends of this mixing chamber I provide screens or perforated plates 21 and 22 whereby the soap issuing from the pipe 17 and the soda issuing from the pipe 18 respectively are broken up into fine streams. As the two sets of streams made by the perforated plates 21 and 22 are oppositely directed, they impact against each other and an intimate mixture results, especially if the temperature of the mixing chamber is maintained at approximately 180° F. for that temperature apparently has critical characteristics.

From the mixing chamber 19, the mixture falls down pipe 23 where it is conducted to the usual atomizing nozzle 24 and blown into the hot chamber 25. Nozzle 24 and chamber 25 are shown in dotted lines because they form no part of this invention. In the hot chamber 25, the soap powder is formed and falls to the bottom of the chamber where it is collected. 75 80

The screens or perforated plates 21 and 22 or any other equivalent means for breaking the liquids up into fine streams, are provided with apertures or openings, the area of which may be varied to suit the relative proportion of the materials it is desired to use. In the event that further mixing is desired, a further screen or screens (or other perforated means) may be used as at 26 and 27 to more thoroughly and intimately mix the two liquids. Also the apertures in these plates may be varied as to size to make a finer or more complete mixture.

This form of apparatus is very effective in carrying out the method involved in this invention and it produces such a thorough, intimate and non-jellying mixture of the soap and the soda that the troubles heretofore experienced in atomizing a mixture of such ingredients, are completely overcome. 10

These troubles have been so serious that soap plants in general have hesitated to go into the manufacture of soap powder, so this invention apparently will now render possible 5 a wide adoption of soap powder making.

What I claim is:

A method for use in soap powder making which consists in heating soap and liquid soda separately, forcing the hot soap and

liquid soda to impact against each other 10 through orifices and forcing the hot mixture through a further atomizing device to further sub-divide, commingle and mix the soap and soda into an intimate non-jellying mixture.

In testimony whereof I have affixed my signature to this specification.

JUDSON A. DE CEW.
